ATTORNEY

UNITED STATES PATENT OFFICE.

WILLIAM G. ENGLE, OF SULLIVAN, INDIANA.

GARMENT-SUPPORT.

1,260,168.

Specification of Letters Patent. Patented Mar. 19, 1918.

Application filed March 23, 1917. Serial No. 156,908.

To all whom it may concern:

Be it known that I, WILLIAM G. ENGLE, a citizen of the United States, residing at Sullivan, in the county of Sullivan and State 5 of Indiana, have invented new and useful Improvements in Garment-Supports, of which the following is a specification.

This invention relates to improvements in garment supports.

10 The object of the invention is to provide a support for garments, such as coats or hats, which is adapted to be secured to the backs of chairs, benches, pews or the like so as to provide a ready and convenient means for 15 the disposal of garments of the occupants.

A further object of the invention is to provide a device of this character which is constructed in such a manner as to occupy the smallest possible space, in order to accommodate 20 it for use between rows of benches, chairs, etc.

A still further object of the invention is the provision of a garment support which is of simple construction, so that it may be 25 cheaply manufactured and at the same time will securely hold the garment thereon in a manner to prevent accidental removal of the same.

With these and other objects in view the 30 invention consists of the following novel combination and arrangement of parts which will be hereinafter more fully described, illustrated in the accompanying drawings and pointed out in the appended claim.

35 In the drawings:—

Figure 1 is a perspective view of a garment support constructed in accordance with the invention;

Fig. 2 is a vertical sectional view; and

40 Fig. 3 is a horizontal sectional view taken on the line with the pivoted member of the U-shaped arm.

Referring in detail to the drawings the 45 numeral 10 designates any suitable support, such as the back of a bench or pew, to which the invention is shown as applied. It is of course obvious that the device may be lengthened and adapted for use in automobiles for supporting the robes. The invention as illustrated 50 comprises a plate 11 which is provided with apertures for the purpose of receiving the fastening device 12, by means of which

the invention is secured to its support. The plate 11 is provided with alined bearings 13, which may be secured thereto in any suitable 55 manner or may be as illustrated formed by striking up a portion of the plate. Mounted within these bearings is one arm 14 of a vertically disposed U-shaped supporting member. The other arm 15 of this member 60 is adapted to swing in an arc away from and toward the support 10 in order to facilitate the placing of garments upon the U-shaped member. The free end of the arm 15 is rounded as shown at 16 to prevent the same 65 from catching into the garments and to facilitate the placing of the garments thereon. The base 17 of the U-shaped member has secured thereto one end of a coiled spring 18, which, surrounds the arm 14 and has its opposite end secured to the plate 11. This 70 spring serves to urge the arm 15 toward the support in order to prevent the garment from slipping from this arm.

It will be seen from the foregoing that 75 the device is simple in construction and may be cheaply manufactured, the plate being formed of any suitable material from which bearings 13 may be struck up. The U-shaped member is formed of a single piece of material, the arm 14 being inserted in the bearings 13 and having its free end bent as shown to prevent possible removal therefrom. It will also be noted that the device occupies very little space so that it is especially 80 adapted for use where space is limited.

Having described the invention, what I claim is:

The combination with a support of an attaching plate secured thereto, laterally extending vertically alined spaced ears formed on said plate, a vertically disposed U-shaped member having one of its arms journaled in the ears of the attaching plate, garment supporting means formed by the other free arm 90 of the U-shaped member, said garment supporting means being free to swing in an arc away from the support and a spring surrounding the first mentioned arm in a manner to normally force the second mentioned 95 arm in contact with the support to clamp the garment between said arm and said support.

In testimony whereof I affix my signature.

WILLIAM G. ENGLE.
